ERICH SCHULZE, OF MAGDEBURG-HOPFENGARTEN, GERMANY, ASSIGNOR TO THE FIRM
FRIED. KRUPP GRUSONWERK AKTIENGESELLSCHAFT, OF MAGDEBURG-BUCKAU,
GERMANY

ROTARY TUBULAR FURNACE

Application filed October 9, 1928, Serial No. 311,272, and in Germany November 11, 1927.

My invention relates to improvements in rotary tubular furnaces—such as used e. g. for metallurgical work, for burning cement and other purposes—and more especially to 5 the construction of the enclosed chute or funnel at the lower end of said furnaces through which the material under treatment passes on being discharged and carried off.

10 The object of the invention is to provide an improved funnel for the purpose set forth which can be easily cleared from molten material, slags and other incrustations deposited on the walls of the funnel, 15 clogging the latter and interfering with the proper discharge of the material under treatment.

Another object of the invention is to design funnels of the kind under consideration 20 the interior of which and of the furnace proper is readily accessible at a moments notice, whenever required for inspection, cleaning or other purposes.

The salient features of my invention are 25 briefly outlined in the appended claims, and its nature will be more fully understood from the following specification and the accompanying drawing in which

Fig. 1 is a vertical cross section taken 30 transversely through the lower end of the furnace and the discharge funnel;

Fig. 2 is a vertical cross section taken 35 longitudinally on line A—B in Fig. 1 through the lower furnace end and the funnel.

The material under treatment on having 40 been heated in the rotary furnace 2 passes through the head or hood 1 of the furnace and drops into the funnel 3 for being discharged and carried off e. g. in small trucks 12.

According to this invention the walls of 45 the funnel are designed so as to be removable by being swung aside or by being carried off respectively in order to make readily accessible the interior of the funnel and of the furnace proper.

In the funnel shown in the drawing by 50 way of an example the front wall 5 is provided with a flap 6, hinged thereto and be-

ing adapted to be swung around, as indicated in dotted lines, thus enabling the operator to control the discharge of the material into the trucks 12.

The side walls 4, 4' of the funnel are 55 hinged to the bottom plate 13 of the furnace head 1 and are capable of being moved into any desired position by means of levers 14; locking devices (not shown) being preferably provided for retaining said flaps in 60 their respective places.

According to this invention the inclined rear wall or bottom plate 8 of the funnel over which the material travels on being discharged is designed so as to be entirely removable. 65

For this purpose the bottom plate 8 is carried on a wheeled frame or pedestal 7, the latter preferably running on rails 17. By wheeling the bottom plate 8 off the funnel 3 70 the other walls of the latter become accessible for cleaning, and even the interior of the furnace head 1 is accessible for inspection, cleaning, repairing and other purposes.

Various modifications may be made in the 75 design and structural details of funnels for rotary furnaces, as described above, without substantially departing from the spirit and the salient ideas of my invention.

For example, cooling appliances may be 80 provided for cooling the walls of the funnel 3, so as to prevent destructive overheating of the latter: In the funnel, shown by way of an example, numeral 9 in Fig. 2 indicates a flexible pipe or hose by means of which 85 water or another cooling medium is supplied to a system of cooling coils 18, mounted at the bottom plate 8.

The cooling liquid on having passed the coils 18 is discharged through a pair of pipes 90 10 into an open drain or gutter 11 the latter being arranged underneath said pipes 10 and extending parallel to the rails 17. Instead of a flexible pipe a pair of extensible 95 trombone pipes may be provided for supplying the cooling liquid and rendering removable the bottom plate 8 in the manner described hereinbefore.

What I claim is:

1. Apparatus for controlling the discharge 100

of material in bulk from rotary tubular furnaces, which comprises a funnel of rectangular cross section attached to the off-take structure of the furnace and having movable walls, the front wall and the adjacent lateral walls, 5 being supported on hinges, so as to be capable of being swung around and thus widening or narrowing the passage for the material to be discharged, means being provided for controlling the angular position of the said lateral walls relatively to each other, the inclined rear wall of the funnel being supported by a carrier adapted to bodily withdraw the rear wall from the funnel.

10 2. Apparatus for the purpose and having the features outlined in claim 1, in which levers are pivotally attached to the lateral walls of the funnel, for manipulating said walls and locking them in their adjusted position.

15 3. Apparatus for the purpose and having the features outlined in claim 1, in which means are provided for cooling the rear wall of the funnel so as to prevent destructive overheating of the latter, said means comprising cooling tubes which are connected with a source of cooling liquid and are adapted to discharge the latter into an open gutter arranged along the path of the carrier supporting the rear wall of the furnace.

20 30 In testimony whereof I have signed my name to this specification.

ERICH SCHULZE.
